Patented Sept. 17, 1968

212,236

FURNITURE PANEL

Richard D. Merillat, Adrian, Mich., assignor to Merillat
Woodworking Company, Adrian, Mich., a corporation of Michigan

Filed May 17, 1967, Ser. No. 7,167

Term of patent 14 years

(Cl. D33—1)

FIG. 1 is a front view in elevation of a furniture panel embodying the invention;

FIG. 2 is an enlarged view in elevation of the lower left corner of the panel as defined by the line 2—2; and

FIG. 3 is a sectional view taken centrally through the panel along the line 3—3.

I claim:

The ornamental design for a furniture panel, substantially as shown and described.
